UNITED STATES PATENT OFFICE.

MARCUS P. NICHOLS, OF ST. PAUL, MINNESOTA.

DESIGN FOR AN OAR-LOCK.

SPECIFICATION forming part of Design No. 30,722, dated May 9, 1899.

Application filed March 30, 1899. Serial No. 711,162. Term of patent 14 years.

To all whom it may concern:

Be it known that I, MARCUS P. NICHOLS, of St. Paul, in the county of Ramsey and State of Minnesota, have invented and produced a new and original Design for an Oar-Lock, of which the following is a specification, reference being had to the accompanying drawings, forming a part thereof, in which similar characters of reference indicate corresponding parts in both figures.

Figure 1 is a front view of an oar-lock embodying my invention, and Fig. 2 is an edge view thereof.

The design comprises an elongated shank *a*, a U-shaped head *b*, the head having an enlargement *c* at the base thereof, and the parallel members *d*, which project from the lower end of the shank and present oppositely-disposed shoulders *e*. The end of the shank be-

tween the members *d* is pointed, as at *a'*, and at the upper ends of the members *d* the sides of the shank present a V shape, as at *a''*.

The leading features of the design consist in the elongated shank presenting at one end a U-shaped head and the parallel members projecting from the other end of the shank at opposite sides thereof, and between which the said end of the shank extends, the said parallel members presenting oppositely-disposed shoulders.

I claim—

The design for an oar-lock, herein shown and described.

MARCUS P. NICHOLS.
